UNITED STATES PATENT OFFICE.

BENSON P. COOPER, OF ITHACA, NEW YORK.

COIN-CONTROLLED DELIVERY APPARATUS.

1,301,391.

Specification of Letters Patent. Patented Apr. 22, 1919.

Application filed October 18, 1917. Serial No. 197,363.

To all whom it may concern:

Be it known that I, BENSON P. COOPER, a citizen of the United States, and resident of Ithaca, in the county of Tompkins and State 5 of New York, have invented a new and useful Improvement in Coin-Controlled Delivery Apparatus; and I do hereby declare the following to be a full, clear, and exact description thereof.

10 My invention relates to apparatus for delivering articles by means of coin-released mechanism, its object being to provide apparatus of this character which is not liable to get out of order, and so simple in construction that any difficulty arising in its 15 use may be readily corrected without the employment of skilled labor.

To these ends my invention comprises the novel features hereinafter set forth and 20 claimed.

In the accompanying drawing, Figure 1 is a vertical side elevation of my improved apparatus, the container for the articles to be sold being broken away; Fig. 2 is a vertical 25 section of my improved apparatus; Fig. 3 is a like view showing dotted-line positions of the different parts; Fig. 4 is an enlarged sectional view taken on the line 4—4, Fig. 1; and Fig. 5 is a view of the end of the cylinder. 30

In the drawing, the numeral 2 designates the casing which incloses the operating parts, and to which is connected the chute 3 for containing the articles to be sold, and 35 which are delivered therefrom to the delivery-trough 4, which is cylindrical in form, with the opening 5 to permit of the discharge of the article therefrom when said delivery-trough is turned in the manner more 40 fully hereinafter set forth. This delivery-trough 4 is mounted to oscillate, and is provided with the trunnions 6 engaging suitable bearings 7 in the casing 2.

A sheave-portion 8 is formed integral with 45 the trough although it may be connected thereto if desired, and made separate therefrom. The sheave portion 8 is provided with the groove 9, which forms a guide or bearing for the coil-spring 10, one end of 50 said spring being connected to the web 11 in the groove 9 of said sheave-portion 8, while the other end of said spring is connected as at 12 to the inside wall of the casing 2.

An operating handle 13 is connected to one 55 of the trunnions 6 for turning the delivery-trough 4.

The end-plate 14 of the delivery-trough has the slot 15 engaging the stud 16 on the casing 2, said stud acting as a stop to control the oscillatory movement of the delivery-trough. The plate 14 is provided with the shoulder 17, which is adapted to engage one end 18 of the dog 19, said dog being pivoted at 20 to the casing 2. A spring 21 connected to the dog 19 bears with its free 60 end against the abutment 22 in the casing, and normally holds said dog down in locking position. The one end 18 of this dog being in the path of the shoulder 17 of the end-plate 14, when the handle 13 is moved 65 the shoulder 17 will engage with the lower end 18 of the dog 19 and further movement of the plate 14, and consequently the delivery-trough 4, is prevented so that the delivery-trough cannot be operated to discharge an article therefrom until freed by 70 the coin, as will more fully hereinafter appear.

In order to prevent tampering with the locking dog 19 and lifting it out of the way 75 so as to permit the movement of the delivery-trough without the insertion of a coin, I provide a guard 23, which consists of an inwardly-extending flange on the casing, which extends in under the dog 19 and prevents 80 anyone by the insertion of a wire or any other instrument, from lifting the dog to release the delivery-trough, and permit its being turned so as to deliver an article therefrom without the insertion of a coin. The 85 coin-receiver 24 has the slot 25, which registers with the slot 26 in the plate 14. Below the plate 14 in the casing is the money-drawer 27.

The coin-receiver 24 is extended up to 90 such height that the one end of the dog 19 cannot be reached by a wire or other instrument inserted in the slot 25, it being apparent, as shown in Fig. 2, that any such instrument 28 when inserted at the extreme 95 angle permitted would not be able to reach the end 18 of the dog 19 to lift same.

In the operation of the apparatus, the coin is inserted in the slot 25 of the coin-receiver, and said coin passes down and engages the 100 flared seat 29 at the upper end of the slot 26. The operating lever 13 is then moved downward and the coin 30 projecting beyond the periphery of the plate 14 will engage the outer end 18 of the dog 19 and said dog will 105 ride up over the periphery of the coin and will be lifted so as to permit the coin to

pass and the delivery-trough to be rotated sufficiently to deliver the article contained therein down into the lower end of the casing to be removed from the opening 31. 5 The movement of the operating-arm 13 is controlled by the end of the slot 15 coming in contact with the stop 6, and during this movement, the spring 10 is expanded, as shown in Fig. 3. When the delivery-trough 10 has been brought into position to deliver the article therefrom, the flared end 29 of the slot 26 will have moved around in such position, as shown in dotted lines, Fig. 3, to discharge the coin into the money-drawer 15 27. Upon releasing the operating-lever 13, the spring 10 will throw the delivery-trough back into normal position as well as the plate 14, and the spring 21 will throw the dog 19 down again into locking position. In 20 such position if anyone attempts to operate the machine without a coin by moving the lever 13, the shoulder 17 will come into engagement with the end of the dog 19 and prevent movement of the delivery-trough. 25 By having the slots 25 and 26 in alinement with each other, the apparatus may be readily cleaned or relieved of any plug or obstruction without removing the machine from the wall to which it is ordinarily secured. By simply opening the money-drawer, the attendant may force a thin piece of steel up through these registering slots and remove any obstruction in the slot— 30 such as tin tags, paper, hairpins, etc.— 35 whereas, ordinarily with apparatus of this character, an expert mechanic is required to do this work. A great saving is effected in this way in that the machine may be installed in isolated places where it is not possible, or not economically possible, to em- 40

ploy an expert to look after machines in such isolated localities.

By simply enlarging or reducing the slot in the coin receiver, the machine can be made to work with any size of coin without changing any other part of the mechanism. Furthermore, by the use of the guard 23 and the raising of the coin-receiver 24, I have made the machine practically fool and burglar-proof. 45

The spring 10 by winding around the sheave member in the manner illustrated and described gives a direct, strong pull, which insures the return of the delivery-trough to the proper position to receive the 50 next article. 55

What I claim is:

1. In coin controlled delivery apparatus, the combination of a suitable casing having a coin chute, one wall of which terminates 60 in an inwardly extending flange, an oscillatory delivery means mounted in said casing, a pivotally mounted dog for locking said means, and said flange extending beneath said locking dog. 65

2. In coin controlled delivery apparatus, the combination of a suitable casing having a coin chute, one wall of which terminates in an inwardly extending flange, an oscillatory delivery means mounted in said casing, and a pivotally mounted dog for locking said means, said flange extending beneath and beyond said dog. 70

In testimony whereof, I, the said BENSON P. COOPER, have hereunto set my hand.

BENSON P. COOPER.

Witnesses:

Mrs. CHAS. SCHRYVER,
AGNES KNICKERBOCKER.
